UNITED STATES PATENT OFFICE.

JOHN C. SHEFFNER, OF CLINTON, WISCONSIN, ASSIGNOR TO CLINTON MANUFACTURING COMPANY, OF CLINTON, WISCONSIN, A CORPORATION OF WISCONSIN.

DESIGN FOR A UNION-NUT.

54,781.

Specification for Design.

Patented Mar. 23, 1920.

Application filed September 5, 1919. Serial No. 322,000. Term of patent 14 years.

To all whom it may concern:

Be it known that I, JOHN C. SHEFFNER, a citizen of the United States, residing at Clinton, in the county of Rock and State of Wisconsin, have invented a new, original, and ornamental Design for a Union-Nut, of which the following is a specification, reference being had to the accompanying drawing, forming part thereof, and in which—

Figure 1 is a plan view, Fig. 2 a bottom view, Fig. 3 a side elevation, and Fig. 4 an end elevation of a union nut, embodying my design.

I claim:

The ornamental design for a union nut as shown.

J. C. SHEFFNER.
